UNITED STATES PATENT OFFICE.

JOHN ROBERT QUAIN, OF LONDON, ENGLAND.

ELECTRIC HEATER.

1,416,872.

Specification of Letters Patent. Patented May 23, 1922.

Application filed July 26, 1920. Serial No. 399,121.

To all whom it may concern:

Be it known that I, JOHN ROBERT QUAIN, a subject of the King of Great Britain and Ireland, residing at 17 Victoria Street, London, S. W., England, have invented certain new and useful Improvements relating to Electric Heaters, (for which I filed applications in Great Britain, No. 12,266, dated July 27, 1918, and No. 13,834, dated Aug. 10 23, 1918,) of which the following is a specification.

This invention relates to electric heaters of the kind in which silica is employed for the support and enclosure of the resistance 15 element or filament.

The object of the invention is to provide a simple and effective immersion heater which may also be adapted for use as a radiator for the heating of rooms and the 20 like.

According to the invention I provide the filament, which may be nickel chrome or any other suitable metallic filament, in the form of a helically wound spiral and I wind 25 the helically wound filament upon the tubular or hollow support and apply between adjacent convolutions a strip of a nonconductor, such as asbestos, or I provide a helical rib on the support and I mount the 30 helically wound filament in the groove between adjacent convolutions of the rib. I advantageously anchor the filament adjacent the end or at the end of the support and form a continuation of it as a wire which 35 returns through the support to the rear end where both ends of the filament are connected to supply conductors.

The support is mounted within a tubular casing of silica, the end of which is closed. 40 The internal diameter of this casing is preferably such that it can be applied upon the support so that the helically wound filament may contact with it.

The casing of silica containing the tubular support and the filament is suitably mounted in a carrier or socket adapted to the particular purpose for which it is required.

It will be understood that on current being passed through the helically wound filament it is rendered incandescent and the adjacent part of the support and enclosing casing are heated.

Such a heater may be used for immersion 55 in liquids for the purpose of heating them

and may be widely used for such purposes. It may also be used as a cigar lighter or as a lighter for other purposes or as a radiator or heater.

The tubular support is provided of silica 60 which possesses the capacity of retaining to a very great degree its resistance to the passage of electric current, even at high temperatures, and thus serves not only as a support to the filament but also as an insulator between the leads, the return lead being conveniently carried through the bore 65 of the support.

It will be understood that the construction of the tubular support may be carried 70 out in various ways. According to one construction it may be a plain tube. According to a modified construction, however, it may be provided with helical ribs formed by moulding the exterior surface of the support or by forming the support upon a helically threaded surface or by preparation in a mould by blowing as in the production of 75 glass work.

I may provide the support for the filament 80 of a composite construction comprising an outer member, which may be of porcelain or like material, threaded or otherwise prepared to receive the filament and an inner member or lining of silica fitting within the 85 outer member.

The application of the invention is illustrated, by way of example, in the accompanying drawings in which—

Fig. 1 represents a heater for use in heating small quantities of liquid;

Fig. 2 is a sectional view corresponding to Fig. 1;

Figs. 3 and 4 are detail sectional views representing modifications in the disposition of the filament;

Fig. 5 represents, to a smaller scale, a heater of large size intended for heating large quantities of liquid;

Fig. 6 is a sectional elevation of a heater 100 for use in baths;

Fig. 7 is a plan view corresponding thereto;

Fig. 8 is a detail view;

Fig. 9 represents diagrammatically a 105 suitable switch device for the heater shown in Figs. 6 to 8;

Fig. 10 represents a heating element which is suitable for a hot water radiator, the outer cage being partly in section;

Fig. 11 represents, a hot water radiator to which a heating element as shown in Fig. 10 is applied;

Fig. 12 represents to an enlarged scale 5 the construction of the socket or carrier for the heating element shown in Fig. 10;

Fig. 13 is a sectional elevation of a heating apparatus in which the heating element is employed for heating rooms and 10 the like; and

Fig. 14 is a sectional view, to an enlarged scale, of a portion of the element used in the apparatus shown in Fig. 13.

In carrying the invention into effect as 15 represented in Figs. 1 and 2, the filament *a* in the form of a helically wound spiral is coiled about a tubular silica support *b* between anchoring studs *b*¹ *b*² fused into the support and between the convolutions is 20 wound the strip of asbestos or other non-conductor *c*. The wire of the filament *a* having been secured to the stud *b*² is led through the support *b* and then back on itself several times and the bundle of strands 25 so formed is twisted together, as at *d*, to form a conductor of relatively low resistance and at the same time to avoid as far as possible the necessity for joints between the filament and other conductors. The 30 other and shorter end of the filament *d* is similarly doubled and twisted. Short lengths of stout copper wire *e* *e*¹ are twisted in with the two ends of the filament wire and connection is made with the flexible supply 35 leads *f* *f*¹ by means of connectors *g* of sheet metal, such as copper, bent around the conductors and gripped thereon under pressure.

The element so provided is mounted in a 40 surrounding casing *h* of silica of an internal diameter sufficient to permit the filament *a* to fit therein. The casing *h* together with the element is secured in a socket *i* by means of asbestos or other suitable 45 washers or packing *i*² compressed to hold the outwardly turned flange *h*¹ of the casing *h* firmly in position in the socket *i* by a gland *i*² adapted to screw into the socket *i*. The latter is provided with a screw threaded 50 recess *i*³ for the reception of a handle *j*. The supply leads *f* *f*¹ are conveniently led away through a bore *j*¹ provided through the socket *i* and the handle *j*. A wire guard or cage *k* is conveniently adapted to be carried upon the flange of the gland *i*².

According to the modification shown in Figure 3, the filament *a* is anchored to the stud *b*² at the extreme end of the support *b* and is then carried into the interior of 60 the support for one or two convolutions in order to secure a concentration of heat at the extremity of the element.

In the modification illustrated in Figure 4 65 the support *b* is provided with a tapering or reduced extremity so that the convolu-

tions of the filament may be carried right to the extreme end to secure efficient heating at the closed end of the casing *h*.

In the production of a portable heater 70 of a large size for use, for example, in heating water in small tanks, as illustrated in Figure 5, the construction is substantially the same as that hereinbefore described with reference to Figures 1 and 2, the modifications made being merely to correspond with 75 the increase in size. The socket *l* is provided to receive the casing *h* containing the element and is provided with a gland *l*¹ screwing into the socket and serving to compress a packing ring after the manner hereinbefore described. The gland *l*¹ is also provided with a centrally disposed opening for the introduction of the supply leads while the socket *l* is provided with a handle *l*² by which the heater may be manipulated. 85 The cage *k* is formed at its extremity with a small strengthening plate *k*¹ which conveniently serves to support spring fingers *k*² serving to hold the casing *h* in a central 90 position.

In carrying the invention into effect as 95 illustrated in Figures 6 to 8 in the construction of a heater which is suitable for use as a bath heater and is adapted to float on the surface of the water, a number of the elements are used having the casings *h* held within socket *m*¹ formed in a hollow circular body *m* adapted to serve as a float, the casings *h* being maintained in position by use of glands *m*² adapted to compress the packing rings *m*³ to engage the casings *h*. They may, however, be mounted in position within the glands in the manner hereinbefore described with reference to Figures 1 and 2 of the drawings. The upper portion of the 105 body *m* is provided with a central opening closed by a cover plate *m*³ which is conveniently provided in a central position with an opening *m*⁴ for the supply leads and which is preferably fitted with a gland *m*⁵ 110 adapted to compress packing around the casing of the supply conductors. The casings *h* are conveniently supported towards their lower end by means of a rod *n* centrally mounted on the hollow body *m* and having at its lower end a substantially rectangular plate *n*¹ at the corners of which there are secured the rings *n*² each serving to embrace one of the casings *h*. Spring fingers *n*³ are conveniently provided upon the rings *n*² to maintain the casings in a centrally disposed position and to guard them against shock. A suitable wire-work 115 casing *o* is fitted around the lower edge of the hollow body *m* and serves as a support for the heater when resting on a surface and feet or legs *o*¹ may be provided on the upper surface of the body *m* to support the heater in the reversed position so that it may serve 120 as a radiator. A pivoted handle *p* may be 125

130

provided upon the float body *m* adapted for attachment or mounting, upon a switch lever *q* (Figure 9) similar to that used on telephones, so that thus on the heater being 5 mounted in position upon the switch lever, the circuit is broken and when the heater is taken off the switch lever, the circuit is closed. By such means the heater is at once available for use without the distinct and 10 separate operation of a switch.

It will be understood that the heater may consist of a number of separate resistance elements in series or parallel. The socket of the heater and the float together with 15 the surrounding frame or cage are advantageously provided of metal but no limitation is involved to their particular shape.

It will be understood that such a heater may be adapted for use for various purposes and for heating water or liquids to 20 any particular degree of temperature. Any other means than those indicated may be employed for mounting the heater in or upon the float in a water-tight manner.

25 In the application of the invention to a hot water radiator as illustrated in Figures 11 to 13 the radiator, is formed in the usual manner of a number of elements *r* which are secured together at their upper and 30 lower ends. At the lower end of one of the outer elements a screw threaded hole is provided co-axial with the lower communicating passage, extending through the elements, to receive a screwed plug *r*¹ which serves 35 as the holder for a heating element constructed in the manner hereinbefore described. The plug *r*¹ is provided on its inner face with a screw-threaded recess to receive the end of the casing *h* of the element and the gland *r*² by which pressure is 40 exerted on the washers *i*² to maintain the casing in position. The gland is also preferably prepared to receive a metal cage *r*³ which serves to protect the heating element. 45 At its outer face the plug *r*¹ is recessed to receive a gland plate *r*⁴ and preferably a washer, the plater *r*⁴ being secured in position by means of screws. It is provided at its outer end with a gland *r*⁵ adapted to be 50 received into a screwed recess to compress a ring of packing or the like around the flexible rubber tube or similar casing *r*⁶ of the leads.

In Figures 13 and 14 is illustrated the 55 application of the heating element according to the invention to a simple form of heating radiator, and also a modified construction of the tubular silica support of the filament. The apparatus comprises a spherically or 60 parabolically formed reflector *s* having mounted at its axis a heating element adapted to screw into a suitable socket *s*¹ of any convenient construction disposed to the rear of the reflector. A number, 65 conveniently three, legs or feet *s*² are mounted

at the rear of the reflector and serve to support it either horizontally or in an inclined position. The heating element is substantially similar in construction to those hereinbefore described but is provided with a 70 tubular support which is of complex form and comprises an inner tube *b* of silica serving to form an effective insulating and supporting member and an outer tube *b*³ of porcelain or the like moulded on its outer 75 surface with a helical rib or thread *b*⁴ serving to separate the convolutions of the filament *a*.

It may be found desirable in some cases to provide the heating element in a surrounding casing which is evacuated after the manner of an incandescent electric lamp. When such construction is adopted the support is mounted in position within the surrounding casing of silica and the adjacent 80 edges at the end, opposite to that at which the filament is mounted, are fused together and a vacuum produced in the annular space between the support and the surrounding casing, or the support and surrounding casing may be mounted within a socket similar to that used for the reception of the bulbs of incandescent lamps.

It will be understood that the invention is not limited to the particular constructions 95 hereinbefore described. For example, in the construction of the support, the convolutions of the filament may be separated by means of a thread of silica fused upon the silica tube. Again in the construction of the holder for the heater shown in Figures 10 to 12, for example, the silica casing *h* may be retained in position within the plug *r*¹ by means of cement instead of by means of the gland. Again, the gland plate *r*⁴ may be 100 screw threaded so as to screw into the plug which is similarly threaded to receive it. Again, with respect to the construction of radiator shown in Figures 13 and 14, other means may be adopted for mounting the reflector. For example, it may be disposed upon a standard in such manner that it may be adjusted in inclination and around the axis of the pedestal or stand.

I claim:

1. An electric heater more particularly intended for use as an immersion heater, comprising a helically wound filament, a support carrying such filament, means for separating the convolutions of the filament, 120 an outer and open silica casing separate from the said support, the said filament extending between the support and the outer casing and a carrier for the casing, substantially as described.

2. An electric heater as set forth in claim 1, wherein the support for the filament is provided of a construction such that it serves to separate the convolutions of the filament, 125 substantially as described.

3. An electric heater as set forth in claim 1, wherein the return wire from the outer end of the filament is carried through the tubular support, substantially as described.
4. An electric heater as set forth in the preceding claim, wherein the return wire is formed by doubling the filament wire several times and twisting together to form a compound conductor, substantially as described.
5. An electric heater as set forth in claim 1, wherein the casing containing the heating element is mounted in the carrier by the use of a compressed packing ring, substantially as described.
6. An electric heater as set forth in claim 1, wherein a number of the heating elements and the corresponding casings are carried by a hollow closed body serving as a float, substantially as described.
7. An electric heater as set forth in the preceding claim, provided with a handle and used in conjunction with a switch serving to support the heater when not in use, the circuit being automatically closed when the heater is removed from the switch, substantially as described.

JOHN ROBERT QUAIN.
